UNITED STATES PATENT OFFICE.

CARL THEODOR THORSSELL AND HARALD LUDVIG REINHOLD LUNDÉN, OF GOTTBORG, SWEDEN, ASSIGNEES TO AKTIEBOLAGET KVAFVEINDUSTRI, OF GOTTBORG, SWEDEN.

PROCESS FOR FIXING NITROGEN.

1,342,834.

Specification of Letters Patent. Patented June 8, 1920.

No Drawing.

Application filed July 9, 1919. Serial No. 309,739.

To all whom it may concern:

Be it known that we, CARL THEODOR THORSSELL, a citizen of Sweden, residing at Köpmansgatan 20, Gottenborg, Sweden, and

5 HARALD LUDVIG REINHOLD LUNDÉN, a citizen of Sweden, residing at Köpmansgatan 20, Gottenborg, Sweden, have invented a certain new and useful Process for Fixing Nitrogen, of which the following is a specification.

10 This invention relates to a process for carrying out chemical reactions in the presence of metals in a finely divided form especially in the production of nitrogen compounds, when this is done by letting the 15 nitrogen react upon a mixture of coal and alkali metals or alkaline-earth metals or their combinations at a high temperature for the forming of cyanid. In such reactions it was long ago known that the reaction is accelerated by adding some metals, for instance iron, manganese, etc. Such an 20 addition of iron has been proposed *inter alia* for instance in the German Patents 25 Nos. 8238, 12350, 18945.

It has, however, become evident that the favorable result of this addition of metals will be still more and essentially increased, if the metal is present in a finely divided 30 form, and this in a higher degree, the finer the metal is divided. A disintegration of this kind may, of course, be carried out by ordinary grinding, but such a grinding is a slow process, especially when the iron, etc., 35 must be very finely disintegrated.

According to the present invention the iron can for instance be added in the form of oxalate of iron, hydroxid of iron precipitated by the wet process or some other cheap 40 iron compound, which does not contain other ingredients besides the iron than hydrogen, oxygen, carbon and nitrogen. When heating the mass in the presence of coal these compounds will be reduced to 45 iron in an extremely finely divided state. This iron is so finely divided that it is often pyrophorous. The mass is heated slowly in such a way that it is kept at a temperature of 500°-600° C. during a time not too

short, when the reduction to metallic iron 50 takes place. In a continuous process this reduction takes place at the preheating of the mass.

As the iron is used repeatedly in the process, it is only needed to add the same once at 55 the start. Thus also iron salts that are somewhat more expensive, such as oxalate, may be used. The solution of oxalate penetrates into the coal and impregnates the same. In this way the iron will be finally 60 divided and at the same time well intermingled.

Hydroxid of iron may also be used to advantage and then it may be produced cheaply in the following manner. A solution of ferrous sulfate is precipitated with ammonia and the ammonium sulfate obtained is recovered. The hydroxid of iron is intermingled in the mass in a moistened 70 condition.

Many other metals, such as manganese, nickel, copper, etc., may be introduced in the mixture of reaction in exactly the same way and lead to the same result.

Having thus described our invention, 75 what we claim as new and desire to secure by Letters Patent is:

In a process for fixing nitrogen and forming cyanids, in which nitrogen is caused to react upon a heated mixture of carbonaceous material and alkali forming metal compounds, in the presence of finely divided metal, preparing said metal by reducing compounds containing no other elements than the metal, hydrogen, oxygen, carbon, 80 and nitrogen, the reduction being carried on at a temperature lower than 550° C. and the metal then being introduced immediately into the zone of reaction.

In testimony whereof, we have signed our 90 names to this specification in the presence of two subscribing witnesses.

CARL THEODOR THORSSELL.

HARALD LUDVIG REINHOLD LUNDÉN.
